(57) **CLAIM**

The ornamental design for a pendant, as shown and described.

DESCRIPTION

FIG. 1 is a front perspective view of a first embodiment of a pendant showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a front perspective view shown in an environment of use wherein the stipple-shaded liquid forms no part of the claimed design;

FIG. 9 is a front elevational view of FIG. 8 wherein the stipple-shaded liquid forms no part of the claimed design;

FIG. 10 is a rear elevation view of a second embodiment of a pendant showing my new design, it being understood that, apart from FIG. 3, all other views of the pendant are the same as those of the first embodiment;

FIG. 11 is a front perspective view of a third embodiment of a pendant showing my new design;

FIG. 12 is a front elevation view thereof;

FIG. 13 is a rear elevation view thereof;

FIG. 14 is a left-side elevation view thereof;

FIG. 15 is a right-side elevation view thereof;

FIG. 16 is a top plan view thereof; and,

FIG. 17 is bottom plan view thereof.

The broken lines shown in FIG. 10 represent portions of the pendant which form no part of the claimed design. The stipple-shaded liquid shown in FIGS. 8 and 9 represents environment and also forms no part of the claimed design.
